UNITED STATES PATENT OFFICE.

FRANK H. HEITGER, OF INDIANAPOLIS, INDIANA, ASSIGNOR TO HEITGER CARBURETER COMPANY, A COMPANY ORGANIZED IN INDIANA.

CARBURETER.

No. 900,731.

Specification of Letters Patent.

Patented Oct. 13, 1908.

Application filed August 24, 1907. Serial No. 389,976.

To all whom it may concern:

Be it known that I, FRANK H. HEITGER, a citizen of the United States, residing at Indianapolis, in the county of Marion and 5 State of Indiana, have invented certain new and useful Improvements in Carbureters, of which the following is a specification, reference being had therein to the accompanying drawing.

10 My invention relates to improvements in carbureters for use in connection with explosive engines and will be hereinafter more particularly described and pointed out in the claims.

15 The object of this invention is to provide a carbureter in which a more perfect admixture of the fluid fuel with the air is accomplished to produce the explosive gas preparatory to its admission into the cylinder

20 or cylinders of the gas-engine to which it is connected; also, to provide a means for more effectually controlling and regulating the supply of the fluid fuel to the fluid fuel reservoir of the carbureter; also, to provide ad-

25 justable means whereby the air admitted to the auxiliary mixing chamber of the carbureter is automatically controlled to properly mix with the atomized or vaporized fluid fuel which is primarily mixed with air in

30 the primary air admission nozzle to obtain the proper explosive mixture to perfect the mixing process. I attain these objects by means of the apparatus illustrated in the accompanying drawings in which like numer- 35 als of reference designate like parts throughout the several views.

Figure 1 is a longitudinal sectional view of my invention of a carbureter: Fig. 2 is a sectional view of the same taken along the 40 line 2—2 in Fig. 1; and, Fig. 3 is a detail view of the bottom portion of the air mixing nozzle showing a portion of the groove and the screen thereof.

I will now proceed to describe the construction and operation of my invention in detail in such clear, and exact terms that others skilled in the art to which it appertains may be able to construct and use the same.

50 This invention of a carbureter is composed of the auxiliary mixing chamber 1, the fluid fuel containing reservoir 2, and

the lower or primary air admission and mixing nozzle 3, which latter is removably secured to the base of the auxiliary mixing 55 chamber 1 and secures said reservoir to the latter as will be hereinafter described.

The bottom air-admission and primary mixing nozzle 3 is provided with a lower sleeve 4 which extends downwardly from 60 the base or larger portion through the center bore of the gasoline reservoir 2 into which it neatly fits and a supporting collar 5 is formed integral on the periphery of and situated on said sleeve in such position as to 65 bear against the raised bearing surface of the under side of the bearing 6 of the reservoir 2 to support said reservoir and secure the top bearing edge of the outer wall of the latter in the counterbore formed in the base 70 7 of the auxiliary mixing chamber 1 to form a close joint therewith when said nozzle 3 is secured in position. The base or larger portion of the admission and primary mixing nozzle 3 is slightly tapered upwardly 75 and is formed like a truncated cone, and said nozzle, at its reduced or smaller portion, is provided with an expanded or spherically formed portion 14 on the top portion of which latter is formed the ejecting nozzle 80 15 which is threaded at its outer periphery to be securely screwed into the similarly threaded bore formed in the base 7 to form a close joint therewith at the same time to be removable so as to detach the reservoir 85 2 when such is desired. The ejecting top end of the air admission and primary mixing nozzle 3 is formed with a tapered or expanding bore with the larger end situated on the top to form the outlet and this form 90 is provided for the purpose of permitting a gradual expansion of the imperfectly mixed explosive compound before entering into the auxiliary mixing chamber 1, to be again agitated and mixed with more air.

95 An elbow 8 is bored to loosely fit on the sleeve 4 to be adjustable thereon and said elbow is removably secured on said sleeve by the bolt 9 the threaded end of which is screwed into the similarly threaded bore of 100 the boss 10 formed on the bottom side of the gasoline duct 11. The gasoline duct 11 is formed integral with the base or larger portion of the air inlet nozzle 3 and the same

extends diametrically across the lower wider open base portion thereof so that each of the open ends of the bore thereof will have said open or inlet ends situated to connect 5 diametrically opposite sides of the peripheral groove 12. The collecting groove 12 is formed around the periphery of the base of the air inlet nozzle 3 to collect the gasoline by which it is surrounded and said groove 10 is surrounded with a wire gauze 12^a which operates as a strainer for preventing sediment or other foreign matter entering said collecting groove and from thence to said duct.

15 The gasoline nozzle 16 is threaded at its bottom end to be securely screwed into the similarly threaded bore of the boss 17 formed integral on the top side of the duct 11, and said gasoline nozzle 16 is of such a length that when secured in position, its top outlet 20 end will be situated at or near the center of the depth of the enlarged portion of said air inlet nozzle or the mixing throat 14 so that the gasoline as it is ejected from the 25 outlet end of said gasoline nozzle will be taken up by and partially mixed with the air as it flows through said throat 14. On the top end of said gasoline nozzle 16 is formed a collar 18 which is flat on its top 30 side and rounded and inclined on its bottom side so as to deflect the incoming air which passes through the throat 14 so as to impart a circular or undulating motion or wave around the exit end of the valve seat or 35 open exit end of the gasoline nozzle 16, not only to prevent the gasoline as it escapes from the gasoline nozzle being forced back but also to create a partial vacuum around the ejecting end of the gasoline nozzle 16 to 40 facilitate the spraying of the gasoline as it is discharged. The baffle collar 18 is situated relatively to the throat 14 of said inlet nozzle 3 so that the rounded bottom portion thereof will be approximately concentric 45 with the center of said throat.

The valve spindle 19 is provided with a screw threaded portion 20 which is adapted to be screwed into the similarly threaded bore of the boss 21 formed integral on the 50 top of the auxiliary mixing chamber 1, and a jam-nut 22 is screwed on said valve stem and adapted to bind on the exterior top trued surface of said boss 21 and the same is provided for the purpose of securing said 55 stem when the needle-valve 23, situated on the bottom end thereof is set at any required position corresponding to a certain quantity of feed of the fluid fuel. A baffle-collar 24, having a flat under surface, is formed on 60 said valve spindle 19, and said collar is situated sufficiently far above the pointed end of said stem or needle-valve 23, that the fluid fuel as it escapes or is ejected from the nozzle 16, after first being divided by said

needle-valve, will impinge against the under 65 flat surface of said baffle-collar to break the outflowing stream or jet of fluid fuel into a spray which spreads radially and outwardly to be taken up by the air as it passes through the throat 14 at which portion of the nozzle 70 3 said spray partially mixes with the air in its passage therethrough to and into the auxiliary mixing chamber 1.

On one side of the fluid fuel reservoir 2 is 75 formed a settling chamber 25 which is situated between the reservoir 2 and the fluid fuel feed chamber 29, so that all the fluid fuel supplied by the feed chamber 29 must pass through said settling chamber to the reservoir 2 which fluid fuel in its passage 80 through said settling chamber may deposit any foreign matter or sediment in said settling chamber, and a needle-valve 26 is provided to close the drain opening 27 formed in the base of said settling chamber. The 85 valve-stem 28 of the needle-valve 26 is screw threaded at its top portion to be screwed into a similarly threaded bore formed in the side wall of said chamber 25, and said stem is of sufficient length to project beyond the exterior side of the wall of said chamber to be readily turned from the outside to open or close said needle-valve. The feed chamber 29 is formed integral on the outer side of the settling chamber 25 and connects with the 90 latter as previously described. In said feed-chamber 29 is situated a center-pin 30 upon which the pivotal end of the arm 31 is pivoted to swing and said arm is of a length sufficient to extend over the settling chamber 100 25 and project into the reservoir 2 sufficiently far to be connected to the float 32 situated in said reservoir. An adjusting screw 33 is revolvably mounted in suitable bearings formed in the upper and lower plates 34 and 105 35 of said float 32, and said screw 33 is screwed into the boss 36 formed integral on the swinging end of the arm 31 so as to adjust said arm 31 relatively to said float and consequently to fix the maximum quantity 110 of fluid fuel to be supplied to said reservoir 2 at one time to maintain a certain predetermined level.

The float 32 is constructed of a suitable buoyant material, such as cork, and said float 115 is made in the form of an annulus of a size to freely operate in said reservoir 2 so as to rise and fall freely as the fluid fuel in said reservoir rises and falls.

The fluid fuel feed valve 37 is formed on 120 the bottom end of the valve-stem 38, and said stem extends upwardly through a bore formed in the arm 31 to and into the bore of the spring containing sleeve 39 to project sufficiently far therein to be connected to the top end of the coil-spring 41. A collar 40 is formed on the valve stem 38 and is so situated thereon to contact with the bottom side 125

of the float arm 31, so that when the fluid fuel in the reservoir 2 falls the float, as it descends, will cause the arm 31 to bear against said collar 40 to open the fluid fuel feed valve 37 to admit a fresh supply of the fluid fuel to replenish the reservoir 2. The coil-spring 41, situated in the spring containing sleeve 39, is preferably made with a smaller or reduced top end which is adapted to be 5 screwed onto the threaded top end of the stem 38 to be readily attached thereto or detached therefrom, while the bottom end of said coil-spring bears or rests upon the bottom end of the bore of said spring containing sleeve 39, which latter is removably secured to the top of the feed chamber 29.

The valve-seat 42 is screwed into the air inlet end of the auxiliary mixing chamber 1 to be removable and the boss 43 thereof is bored and threaded into which threaded bore is screwed the valve guide and adjusting stem 44, and a jam-nut is screwed on said stem to be situated exteriorly of said boss, and the same is provided for the purpose of 20 securing said stem 44 when adjusted to fix the tension of the valve closing spring 45. The air inlet valve 46 is bored centrally to loosely fit and slide on said stem 44, and said valve is adapted to seat against the trued 25 bearing surface of the valve seat 42. A spring centering cup 47 is also bored centrally to loosely fit and slide on said stem 44 with the valve 46, and said spring centering cup is yieldingly held in contact with the 30 valve 46 by the spiral spring 45 which latter is made in the form of a cone with its larger or base end situated to bear against and be situated in the cup of the spring centering cup 47 and its smaller end reduced to such a 35 diameter as to fit over the end of the stem 44 to which it is secured, so that the tension of said valve spring may be readily adjusted by turning said stem 44 either to the right or to the left the desired amount to regulate 40 the admission of air into the auxiliary mixing chamber 1. On the opposite end of the chamber 1 is situated a connecting-nipple 48 whereby the carbureter is connected to the engine pipe. A throttle valve 49 is secured 45 on the stem 50 which latter is pivoted in the bore of said nipple to be revolved therein, and said stem projects through the top of said nipple sufficiently far to receive the lever 51 on said projecting outer end. The 50 lever 51 is connected to suitable mechanism to be under the control of the operator, so that said throttle may be manipulated to regulate the opening of said nipple to control the admission of the explosive mixture 55 to the engine.

A baffle-plate 53 is situated between the air inlet valve 46 and the outlet end of the nozzle 3 and said baffle-plate 53 is formed integral with the base 7 and extends across

the interior of the auxiliary mixing chamber 65 1 to connect at its ends to the walls of said auxiliary mixing chamber, and said baffle-plate is curved at its upper portion to be inclined over the outlet or nozzle-end 15 of the primary mixing nozzle 3 for the purpose of 70 deflecting the air, as it is admitted by the inlet valve 46, upwardly to create a partial vacuum over said outlet or nozzle end of said primary mixing nozzle to assist the discharge of the explosive mixture therefrom into said auxiliary mixing chamber to mix with the 75 air contained therein.

A spring latch 54 is fitted into the bore formed in the bottom of the boss 55 to slide longitudinally therein and said latch is situated so as to be moved into contact with the back of the valve 46 to lock the same in closed position to prevent the admission of air into the auxiliary mixing chamber 1, so that air is only admitted to said chamber 80 through the primary mixing nozzle 3 thereby rendering the explosive mixture richer in hydrocarbon when such is required.

A spring protecting cap 56 is secured on the top end of the latch 54 which fits into the bore of the boss 55 to slide longitudinally therein, and said cap operates as an inclosing and protecting shield for the top portion of 85 said coil-spring.

On one side of the boss 55 is formed the 90 arm 58 on the end of which is pivotally connected the bell-crank lever 59, one arm 60 of which is rounded on its under side to form a bearing contact with the top closed end of the cap 56, the other arm 61 of said bell-crank lever being arranged to be connected to a suitable connecting mechanism whereby the operator may conveniently operate said 95 spring-latch to lock said inlet valve 46 closed to prevent the admission of air into the auxiliary mixing chamber 1.

The operation of this carbureter is as follows:—Suppose the carbureter connected to an explosive engine of any of the usual well known types of explosive-engines and that 100 said engine has been put in motion to start the same so as to create a vacuum to draw a charge of the explosive mixture into the auxiliary mixing chamber 1 of the carbureter, then under this condition, the atmospheric air first enters the elbow 8, then, through the sleeve 4, to and through the primary mixing nozzle 3, thence through the throat 14 where said air takes up the atomized hydrocarbon and thence to and through the nozzle 15 into 105 the auxiliary mixing chamber 1. The partial vacuum created by the starting of the engine also draws a quantity of the fluid fuel through the outlet of the nozzle 18 which, in its discharge, impinges first against the 110 pointed end of the needle-valve 23 which causes said fluid fuel to slightly spread and impinge against the under flat surface of the 115

baffle collar 24 to break the divided jet of fluid fuel into a fine spray to be absorbed or taken up by the air in passing through the throat 14 to the nozzle 15 to be discharged therethrough and therefrom into the auxiliary mixing chamber 1. The explosive mixture may be further mixed with atmospheric air in the auxiliary mixing chamber 1 in which case the spring 45 is so adjusted that the valve 46 will open simultaneously with the flow of the air through the primary mixing nozzle 3, so that said explosive mixture, as it flows from the ejecting nozzle 15 into said auxiliary mixing chamber, will commingle and mix with the air contained in said auxiliary mixing chamber to reduce the quantity of hydrocarbon in the resulting mixture. The volume of hydrocarbon relative to the air admitted into the carburetor is proportional to the vacuum created in the auxiliary mixing chamber 1 and this vacuum is entirely controlled by the throttle valve 19 situated in the nipple 48 and also the air admission valve 46, which is automatically controlled by its closing spring 45.

When the explosive mixture is required to be rich in hydrocarbon, as when starting the engine, the valve 46 is locked closed, as previously described, so that all the air admitted into the auxiliary mixing chamber 1 must pass through the primary mixing nozzle 3, in which case the amount of hydrocarbon taken up by the incoming air may be regulated and controlled by the needle-valve 23.

I claim:—

1. In a carburetor, the combination with a fluid fuel supplying nozzle, a valve seat situated at the top end of the latter, a throat surrounding the top end of said nozzle, an air admission nozzle extending downwardly from the open base end of said throat and terminating in an enlarged air inlet end, an ejecting nozzle extending from the top outlet end of said throat terminating in an enlarged ejecting end, and an air deflecting collar on the top end of said fluid fuel supplying nozzle having its under surface inclined and situated to be approximately parallel with the inner lower surface of said throat, of a valve stem, a valve coacting with said valve seat on the end of said stem, a deflecting collar situated on said stem above said valve having its flat under surface situated to be impinged against by the outflowing jet of fluid fuel from the fluid fuel supplying nozzle.

2. In a carburetor, the combination with a fluid fuel supplying nozzle, a valve seat situated on the top end of the latter, a spherically formed throat surrounding the top end of said nozzle, an air admission nozzle connected to the inlet open base end of said throat, said air admission nozzle gradually

expanding to its enlarged open air inlet end, and an ejecting nozzle connected to the top outlet end of said throat, said nozzle having its bore gradually expanded toward its outlet end, of an air deflecting collar situated at the top end of said fluid fuel nozzle having its under surface approximately concentric with the inner lower surface of said throat, a valve stem, a valve on the end of said stem coacting with said valve seat, and a deflecting collar situated on said stem above said valve so that its flat under surface will be impinged against by the outflowing jet of fluid fuel from the fluid fuel supplying nozzle.

3. In a carburetor, the combination with a fluid fuel supplying nozzle, a valve seat on the top end of the latter, an air admission and primary mixing nozzle having a fluid fuel collecting peripheral groove situated at or near the base thereof, a strainer surrounding said groove, a fluid fuel supplying duct integral with and extending across the open base of said air admission and primary mixing nozzle to connect the collecting groove and said fluid fuel supplying nozzle, an auxiliary mixing chamber connected to the open ejecting end of said air admission and primary mixing nozzle, and a fluid fuel reservoir surrounding said latter nozzle, of a needle-valve coacting with said valve seat and a deflecting collar situated above said valve and having its flat under surface so situated above said needle-valve as to deflect the fluid discharged from said fluid fuel supplying nozzle.

4. In a carburetor, the combination with a fluid fuel supplying nozzle, a valve seat on the top end of the latter, an air admission and primary mixing nozzle having open base air inlet and top outlet ends surrounding said fluid fuel supplying nozzle, a fluid fuel reservoir surrounding said air admission and primary mixing nozzle, and a fluid fuel supplying duct connecting said reservoir and said fluid fuel supplying nozzle, of an auxiliary mixing chamber, having opposing inlet and outlet openings, arranged to be connected to the outlet end of said air admission and primary mixing nozzle so that the latter will be situated intermediate the opposing inlet and outlet ends of said auxiliary mixing chamber, and a baffle-plate extending across said auxiliary mixing chamber and situated adjacent the inlet end thereof, said baffle-plate having a curved top portion arranged to extend partially over the outlet end of said air admission and primary mixing nozzle.

5. In a carburetor, the combination with an auxiliary mixing chamber having an air admission opening situated at one end of said chamber and an opposing outlet open-

ing, of a fluid fuel supplying nozzle, a valve coacting with said nozzle, an air admission and primary mixing nozzle surrounding said fluid fuel supplying nozzle having its open top end connected to said auxiliary mixing chamber intermediate the air admission and outlet ends thereof and a baffle-plate extending transversely of said auxiliary mixing

chamber and intermediate the air admission end and primary mixing nozzle. 10

In testimony whereof I affix my signature in presence of two witnesses.
